TREATMENT OF HYDROCARBON OIL

Vladimir Ipatieff, Chicago, Ill., assignor to Universal Oil Products Company, Chicago, Ill., a corporation of Delaware

Application January 16, 1933, Serial No. 652,008

5 Claims. (Cl. 260—168)

This invention relates more particularly to the manufacture of hydrocarbons of suitable boiling point for use as components of motor fuel.

In a more specific sense the invention has reference to a process which both conserves materials which are ordinarily considered as waste products in cracking processes and at the same time produces hydrocarbons having specially high anti-detonating characteristics.

10 Owing to the adoption of high compression ratios in automobile engines to increase their thermodynamic efficiency, a demand has been made upon the petroleum refining and other industries which furnish hydrocarbon motor fuels, for fuels 15 of a high anti-knocking and slow-burning character. The cracking process which generally produces both unsaturated hydrocarbons and cyclic hydrocarbons due to the primary dehydrogenating and secondary condensing character of the 20 decomposition reactions is employed quite generally to meet the demand for a high anti-knock motor fuel. However, complete control of the proportion of cyclic hydrocarbons to olefins is not always possible as the character of the charging oil varies with the type of crude from which 25 they are produced, and when intensive cracking conditions are employed in an effort to increase the amount of cyclic hydrocarbons and hence the anti-knock value, undesirably large losses in gas 30 and coke may be encountered and frequently the amount of olefins, particularly those of a highly unsaturated and unstable character, may increase roughly in proportion to the increase in aromatics and other cyclic hydrocarbons.

35 The fixed gases produced in cracking processes contain notable amounts of the normal olefins, including ethylene, propylene, and butylenes and other gases of a more highly unsaturated and still more reactive character such as iso-olefins, 40 acetylene, butadienes, et cetera. Extensive experimenting has been conducted to find ways of utilizing the reactive constituents of gases from cracking plants and convert them into more valuable products.

45 The present process enables the effective utilization of the olefinic constituents of cracked gases and similar olefins produced in any manner.

In one specific embodiment the present invention 50 comprises treatment of aromatic or similarly reactive cyclic hydrocarbons with olefinic or unsaturated gases in the presence of catalytic agents comprising mixtures of phosphoric and sulfuric acids.

55 I have determined that better and more controllable results are obtainable when alkylating

aromatic or similarly reactive hydrocarbons with olefins of diverse character when using suitably proportioned mixtures of sulphuric and phosphoric acids than when using either acid alone. 5 Sulphuric acid is a very energetic catalyst for such reactions and causes the ready combination of normal mono olefins with aromatic hydrocarbons to produce valuable alkylated derivatives. In the case of more reactive olefins such as iso-olefins or di and tri-olefins, however, there is a pronounced tendency toward polymerization so that 10 this type of change occurs in preference to the addition of the olefin molecules to the aromatics. The polymerization reactions may proceed to the extent of forming polymers of too high molecular 15 weight and boiling point for use in commercial motor fuels and may even produce gummy and resinous polymers which are insoluble and entirely objectionable for this reason.

20 Phosphoric acid on the other hand has a more moderate action in contrast to sulphuric acid, and fosters the interaction of the more reactive olefins with aromatics instead of inducing their polymerization. Consequently, by utilizing suitably proportioned mixtures of sulphuric and phosphoric acids in reactions involving the alkylation of aromatics by different types of olefins such as occur in gases from hydrocarbon oil cracking processes it is possible to obtain a high percentage 25 of alkylation along with a practical minimum of 30 polymerizing reactions. There is a higher yield of desirable low boiling product with the minimum undesirable sulphur content. It is not to be inferred, however, that polymerization can be entirely obviated since the catalytic acid mixtures 35 are not miscible with the hydrocarbons and only multi-phase reactions are possible, which leaves the question of effective contact between reacting constituents to the efficiency of mechanical agitation and mixing.

40 The reactions between olefins and aromatics in the presence of condensing catalysts such as sulfuric-phosphoric acid mixtures are basically of a simple character, although there is always a certain amount of side reactions resulting in small losses of acid and oxidation of the hydrocarbons. 45 Apparently the intermediate-compound theory of catalysis best explains the observed reactions, which means in the present instance that both 50 types of reacting components form primarily transient addition compounds with the acid catalysts which then further react to produce the synthetic hydrocarbons and regenerate the acids. The following equation represents the course of a 55

typical reaction induced between a mono-olefin and an aromatic by sulphuric acid:

10 The reaction which takes place when iso-butylene is reacted with benzol in the presence of phosphoric acid is characteristic of reactions induced by this acid and may be expressed by the following equation:

- 15 This equation shows the union of one molecule each of iso-butylene and benzol. The reactions in both cases may proceed further to the production of di and even tri-alkyl derivatives, depending upon conditions of operation, the relative proportions of olefins and aromatics and the usual controlling factors such as temperature, pressure and efficiency and time of contact.

20

25 Sulfuric acid which comprises one of the components of the acid mixtures which may be employed is sufficiently familiar to those engaged in commercial chemical operations and particularly in petroleum refineries to require any detailed description of its properties. It may merely be stated that it is completely soluble in water and that acids of any strength from a very dilute acid to solid sulfur trioxide are available for use. There is evidence of the existence of both a di and a mono hydrate corresponding to the following formulas:

The dihydrate corresponds to approximately 30% H_2SO_4 solution and the mono hydrate constitutes 100% sulfuric acid.

Below is given a tabulation of the known acids of phosphorous along with their melting points and temperatures of decomposition:

45	Acids of phosphorus	m. p. °C.	Dec. °C.
	Hypophosphorous H_3PO_2	26.5	Above m.p.
	Orthophosphorous H_3PO_3	70.0	200
	Pyrophosphorous $H_4P_2O_7$	38.0	130
	Hypophosphoric $H_4P_2O_6$	55.0	70
50	Metaphosphoric HPO_3	Sublimes	
	Pyrophosphoric $H_4P_2O_7$	61	
	Orthophosphoric H_3PO_4	38.6	Loses $\frac{1}{2}$ H_2O at 213.

55 Of those listed the use of the more ordinary and stable acids is preferred, to wit, the orthophosphoric acid H_3PO_4 and the orthophosphorous acid H_3PO_3 , these being used alternatively in different mixtures though without identically equivalent results.

60 In conducting operations leading to the production of hydrocarbons according to the process of the present invention, individual olefins or mixtures of olefins such as occur in gases from oil cracking plants may be introduced into well agitated suspensions of sulfuric-phosphoric acid mixtures in liquid aromatic hydrocarbons. Moderately superatmospheric temperatures are suitable such as those in the neighborhood of 60° C. in the case of the olefins present in such commercial gas mixtures as those encountered in oil cracking processes. It is generally necessary to use relatively concentrated acids and a considerable quantity in relation to the volume of liquid aromatics, since the phosphoric acid component of the catalyst mixture undergoes substan-

Finally no deterioration and the sludge sulphuric acid is readily regenerated. When tests have shown that the desired degree of alkylation of the benzol has taken place, the gas stream may be stopped and the hydrocarbon layer separated from the acid.

The foregoing procedure is of a very simple character and in commercial practice may be modified to permit the use of ordinary batch and continuous treating plants which are familiar to 10 petroleum refinery operators. For example, a mixture of sulphuric and phosphoric acid and aromatic oil may be circulated by centrifugal pumps taking suction at the bottom of a batch agitator and discharging back into the top. Such 15 operation may be conducted to permit the separation and continuous removal of alkylated aromatics and if necessary the recycling of the gases.

As a further alternative method of operation, an olefinic gas mixture, for example, the fixed 20 gases from an oil cracking plant, the requisite amount of aromatic oil and catalytic acid mixture may be injected into a suitable mixer positioned in the upper portion of a treating tower containing filling or spacing material, all reacting components passing downwardly through 25 the interstices to effect substantially complete reaction. The gases denuded of reactive olefins may be separated in subsequent receivers and the acid and liquid hydrocarbon layers either returned to the treater or finally removed. As 30 a general rule the acid may be cycled for a long time before it is contaminated to an extent rendering its use uneconomical.

A large number of examples are available to show the improved results obtainable by the use of mixed sulphuric-phosphoric acids according to the process of the present invention. The following case, involving the interaction of definite compounds, to-wit, n-butylene, with benzol, is selected principally for the reason that the efficiency of the process may be more easily gauged from analytical data. 35 40

A series of experiments were conducted in which n-butylene was passed as a gas into well-stirred mixtures of benzol and differently proportioned acid mixtures. The temperature used in all tests was 60° C. (140° F.). The results of the series of tests are shown in graphic form in Figs. 1, 2, 3 and 4 attached and indicate that in the case of this particular combination of olefin and aromatic that the greatest over-all efficiency in producing anti-knock gasoline boiling range hydrocarbons was obtained by the use of an acid mixture consisting of 40% sulphuric acid and 60% phosphoric acid, the phosphoric acid being of 85% concentration and the sulphuric acid being of the 96% grade.

Referring to Fig. 1, it is seen that the volume increase of the benzol layer after passing in n-butylene for a period of three hours passed through a maximum when using an acid mixture of 60% phosphoric and 40% sulphuric acid as stated, the yield dropping off sharply at either side of this point.

In Fig. 2, curve A shows a maximum for the particular mixture mentioned in the increase in weight of the hydrocarbon layer and curve B shows that the weight increase of the acid layer 70 (or in other words, the sludge formation) was still at a small value when the maximum weight increase of benzol was obtained.

The curve in Fig. 3 shows the initial boiling point of the mixture of alkylated hydrocarbons 75

produced and indicates that the initial boiling point increases up to a mixture comprising 20% phosphoric and 80% sulphuric acid. Obviously, in the case of the two selected reactants under 5 consideration the initial boiling point of the mixture was due to residual unaffected benzol.

Fig. 4 shows the percentage of material in the alkylated mixture boiling below 225° F., which temperature marks the usual upper boiling point 10 limit allowable in present day gasolines. It is seen in this case that for the most desirable acid mixture in respect to yield of production that a certain percent of components boiling above the gasoline range are obtained. In this case the 15 matter of economy would dictate a certain balance between yield and quality of product.

While the foregoing example involving pure compounds is sufficiently indicative of the accurate control of alkylation reactions which is 20 possible when using varying mixtures of sulphuric and phosphoric acids, the process of the invention is adaptable to any case involving on the one hand mixtures of olefins such as may be obtained when cracking either gaseous or liquid 25 hydrocarbons and, on the other hand, aromatics or other reactive cyclic hydrocarbons. The factors of temperature, pressure, rate of introduction of the olefins into contact with the aromatics and the acids may be adjusted to obtain 30 the best results in any given case. Factors of major influence are the chemical characteristics of the olefins comprised in any commercial gas mixture which may be employed. When mono 35 olefins predominate, the percentage of sulphuric acid in the acid catalyst mixture may in general be increased, since this will increase the speed of the reactions without producing an undue amount of polymerization; whereas, if the gas mixture contains a relatively large amount of 40 highly reactive olefins such as unsymmetrical iso-olefins or di and tri-olefins, the proportion of phosphoric acid may be raised.

The foregoing specification and the example 45 and figures appended will serve to make clear the nature of the present invention in relation to the art to which it pertains, but the particular data given is not to be construed in any sense

as imposing undue limitations on its generally broad scope.

I claim as my invention:

1. In the alkylation of cyclic hydrocarbons capable of condensation with olefins, the improvement which comprises reacting the cyclic hydrocarbon with the olefin in the presence of a catalyst consisting predominantly of a mixture of phosphoric and sulphuric acids in substantial 10 proportions.

2. In the alkylation of cyclic hydrocarbons capable of condensation with olefins, the improvement which comprises reacting the cyclic hydrocarbon with a gaseous olefin in the presence of a catalyst consisting predominantly of 15 a mixture of phosphoric and sulphuric acids in substantial proportions.

3. The method of producing alkylated derivatives suitable for use in motor fuel, which comprises reacting an aromatic hydrocarbon of the 20 benzene series and boiling within the motor fuel range with a gaseous olefin in the presence of a catalyst consisting predominantly of a mixture of sulphuric and phosphoric acids in substantial 25 proportions.

4. The method of producing compounds suitable for use in motor fuel which comprises subjecting benzol at moderate temperature to the action of an olefinic gas in the presence of a catalyst consisting predominantly of a mixture of 30 phosphoric and sulphuric acids in substantial proportions.

5. The method of producing compounds suitable for use in motor fuel which comprises treating an aromatic hydrocarbon of the benzene series boiling within the gasoline range, in the presence of a catalyst consisting predominantly of a mixture of phosphoric and sulphuric acids in substantial proportions, with the olefinic gas mixture produced in the cracking of hydrocarbon 40 oil, reacting olefins contained in the gas mixture with the aromatic hydrocarbon under conditions to produce a substantial quantity of alkylated derivatives within the gasoline boiling range, and recovering the gasoline boiling derivatives 45 thus formed.

VLADIMIR IPATIEFF.
